ABRASIVE TYPE HANDTOOL

Robert W. Martin, 1057 Pennington Road,
Trenton, N.J. 08618

Filed Apr. 1, 1969, Ser. No. 16,541

Term of patent 14 years

Int. Cl. D8—02

U.S. Cl. D8—90

FIG. 1.

FIG. 2.

FIG. 3.

FIG. 1 is a perspective of an abrasive type handtool embodying the novel design of the present invention;

FIG. 2 is a side elevation of the abrasive type handtool illustrated in FIG. 1; and

FIG. 3 is an end view of the abrasive type handtool illustrated in FIG. 1.

I claim:

The ornamental design for an abrasive type handtool, as shown.
